UNITED STATES PATENT OFFICE.

HENRY E. HUBBARD, OF OAK PARK, ILLINOIS.

RESETTING DEVICE.

1,266,807.

Specification of Letters Patent. Patented May 21, 1918.

Application filed November 13, 1916. Serial No. 130,980.

To all whom it may concern:

Be it known that I, HENRY E. HUBBARD, a citizen of the United States, residing at Oak Park, in the county of Cook and State 5 of Illinois, have invented certain new and useful Improvements in Resetting Devices, of which the following is a specification.

This invention relates to registering and recording mechanism and has for its primary object the provision of means whereby 10 a plurality of disks each bearing digits arranged in their natural sequence about the periphery thereof may be quickly and easily rotated to automatically return the disks to starting position regardless of the relative 15 angular position of the corresponding digits on the disks.

Further objects and advantages of my invention will be apparent as it is better understood by reference to the following specification when read in connection with the accompanying drawing, illustrating the preferred embodiment thereof, in which

Figure 1 is a plan view of a series of disks 25 arranged to be rotated according to my invention;

Fig. 2 is a section through the structure illustrated in Fig. 1;

Fig. 3 is a section on the line 3—3 of 30 Fig. 2;

Fig. 4 is a section on the line 4—4 of Fig. 2, and

Fig. 5 is a section on the line 5—5 of 35 Fig. 2.

Referring to the drawing, 1 indicates a suitable frame or support adapted to provide journals for a rotatable shaft 2. A knurled head 3 at one end of the shaft 2 provides means for rotating the latter, although it is to be understood that where my invention is employed in connection with gangs of numbering machines the knurled head 3 may be replaced by a gear or other means for transmitting power to and rotating the shaft. Loosely mounted on the shaft 2 and in the present instance held against lateral movement by washers 4 are a plurality of disks 5 each bearing a series of digits in their natural sequence. The disks 40 5 are independently rotatable being provided with ratchets 6 which may be actuated by any suitable mechanism to successively rotate the disks representing units, tens, etc., in the ordinary and well-known manner.

The shaft 2 is provided with a notch 7 45 and each of the disks 5 is provided with a

member 8 slidable in a suitable guideway therein and provided with a tongue 9 adapted to engage the notch 7. A spring 10 disposed in a groove in each of the disks 5 is 60 adapted to bias the members 8 toward the shaft 2 so that when the notch 7 is in proper relative position the tongues 9 will be forced into the notch. Obviously when the tongues 9 are so engaged the disks 5 are 65 rotatable with the shaft 2. In the intermediate disks 5 the members 8 project through to the periphery of the disks (Fig. 4) and carry the zero, and the tongues 9 are of such depth that when the tongues are not 70 disposed in the notch 7 the zeros are raised to the normal height of the remaining digits but when the tongues 9 are in the notch 7 the zeros are below their normal position and are, therefore, out of printing position. 75 In the units disk the member 8 does not extend through to the periphery of the disk, the guideway being bridged at 11 (Fig. 5) to support the digit "1." The disk 5 at the opposite side of the series is similarly constructed but the bridge is blank. A plunger 12 within the frame 1 is biased by a spring 13 to engage a notch 14 in the shaft 2 when the latter has been rotated to a predetermined angular position. 80

The mode of operation of my invention will be apparent from the following brief description thereof. The disks 5 being in the positions indicated in Fig. 1 are successively actuated counting from "1" upward 85 until the operator desires to reset the mechanism. By grasping the knurled head 3 the shaft 2 may be rotated and regardless of the relative angular positions of the corresponding digits on the respective disks they 95 will be successively picked up during the rotation of the shaft 2 by engagement of the tongues 9 with the notch 7 until all of the disks are brought to a position in which the corresponding digits thereon are in 100 alinement. A single rotation of the shaft 2 is sufficient in every case to reset the disks in the position indicated in Fig. 1.

From the foregoing it will be apparent that I have perfected a simple mechanism 105 whereby the tedious operation of resetting each individual disk manually by the use of some sharp pointed instrument (as has heretofore been customary) is entirely obviated. The simple operation of rotating 110 the shaft through a single revolution is sufficient to automatically bring the corre-

sponding digits on the various disks to the desired alinement and the counting operation may begin at once anew. My invention is not only desirable in manually operated numbering machines adapted to print numbers but is equally advantageous when used in connection with either recording or registering counters which are mechanically operated to indicate the number of operations performed by machines of various kinds. In certain classes of numbering, gangs of machines are employed embodying sometimes hundreds of disks which according to the old method must be laboriously returned to zero position at intervals. By connecting the various shafts to a single manually operable member and embodying my invention in the machines all of the disks may be practically instantaneously reset.

It will be apparent that various changes may be made in the form, construction and arrangement of the parts without departing from the spirit and scope of the invention or sacrificing any of its material advantages, the form hereinbefore described being merely a preferred embodiment thereof.

I claim:

1. In a device of the character described, the combination of a rotatable shaft, a plurality of number disks revolvably mounted thereon, radially movable zero members in said disks, means on the shaft and said members for effecting operative engagement thereof, and means for rotating the shaft after one or more of the disks have been advanced to restore all the disks to initial position.
2. In a device of the character described, the combination of a rotatable shaft, a plu-

rality of number disks revolvably mounted thereon, radially movable zero members mounted in said disks and depressed in initial position, means on the shaft and said members for effecting operative engagement thereof, and means for rotating the shaft after one or more of the disks have been advanced to restore all the disks to initial position with the movable members depressed.

3. In a device of the character described, the combination of a rotatable shaft, a plurality of number disks revolvably mounted thereon, radially movable zero members in said disks, springs acting on said members to hold them normally depressed in initial position, means on the shaft and on the inner ends of said members for effecting operative engagement thereof, and means for rotating the shaft after one or more of the disks have been advanced to restore all the disks to initial position with the movable members depressed.

4. In a device of the character described, the combination of a rotatable shaft, a plurality of number disks revolvably mounted thereon and provided with annular grooves, radially movable zero members in said disks, springs in said grooves and engaged with said members to hold them normally depressed in initial position, means on the shaft and on the inner ends of said members for effecting operative engagement thereof, and means for rotating the shaft after one or more of the disks have been advanced to restore all the disks to initial position with the movable members depressed.

HENRY E. HUBBARD.
